J. J. C. BRAND

APPARATUS FOR FIRING FURNACES WITH POWDERED FUEL

Original Filed March 7, 1919

FIG. 2

FIG. 1

FIG. 3

Inventor
J. J. C. Brand,
By Marks Clerk
Atty's

UNITED STATES PATENT OFFICE.

JAMES JOHN CANTLEY BRAND, OF SYDNEY, NEW SOUTH WALES, AUSTRALIA.

APPARATUS FOR FIRING FURNACES WITH POWDERED FUEL.

Original application filed March 7, 1919, Serial No. 281,189. Divided and this application filed July 11, 1921. Serial No. 483,910.

To all whom it may concern:

- Be it known that I, JAMES JOHN CANTLEY BRAND, subject of the King of Great Britain and Ireland, residing at Garden Island, 5 Sydney, New South Wales, Australia, have invented new and useful Improvements in Apparatus for Firing Furnaces with Powdered Fuel, of which the following is a specification.
- 10 This invention relates to an improved burner to facilitate complete combustion of powdered fuel in boilers, and constitutes a division of my former application Serial No. 281,189, filed March 7, 1919.
- 15 In the accompanying drawings:—
- Fig. 1 is a vertical section through a nozzle and hot box;
- Fig. 2 is a horizontal part section on the line 2—2 Fig. 1;
- 20 Fig. 3 is a sectional elevation on the line 3—3 Fig. 1.
- The fire door end of the furnace flue is extended forwardly at a greater or less distance for the purpose of shielding the flue 25 plates of the boiler from injuriously excessive temperatures. The fire doors 1 are mounted in the extension end plate 2 and behind said plate an air chamber 3 is contained forwardly of the fire brick dia-
- 30 phragm 4. The burner nozzle 5 is outwardly flared and fitted internally with a mouth cone 6 which operates to spread the blast as a conical annulus. It is water jacketed as shown at 7 and fitted with a tubular 35 collar 8, having vents 9 cut around it placing the annular air collar space 10 in connection with the chamber 3 which is connected through a pipe 11 with an air blast pipe (not shown). The air blast into this 40 chamber is preferably heated. The collar vents 9 are formed tangentially as shown in Fig. 2 for the purpose of applying whirling motion to the air passing from the chamber 3 through them into the collar space 10
- 45 surrounding annular mouth 12 of the nozzle. The nozzle is withdrawable without disturbing its relation to the conical collar 8 when the fire doors 1 are opened. To facilitate its withdrawal, the nozzle is mounted 50 on the end of a furnace feed pipe 20 by a slip joint 18.

In the end of the pipe 20 a helical vane 14 is fitted to produce a whirling motion of the fuel as it enters the furnace. The direction of the rotation of the fuel blast and of the air blast in the collar correspond. Within the furnace flue 15 directly in front of the nozzle a checker work fire brick hot box 16 is constructed. Initial combustion takes place in this box which becomes incandescent and the flaming gases therefrom pass through the checker vents into the furnace flue 15 and thence through the tube system of the boiler passing out as usual through the smoke box 17 to the up-take (not shown). 60

18 and 19 are inlet and outlet connections of the water jacket 7. They are connected by flexible pipes to cooling water service and eduction pipes. The air pressure connections may be valved so that the blast through 70 the nozzle collar 8 is readily controllable.

What I claim as my invention and desire to secure by Letters Patent is:—

1. A burner for the purpose described comprising a water jacketed flared nozzle, a collar surrounding and spaced from said nozzle, an air blast box enclosing said collar and supplying pressure air thereto, said collar having apertures leading from the air blast box to the interior of the collar and a fire brick hot box constructed of open-work fire brick located in front of the burner nozzle. 75

2. A burner for the purpose described comprising a fuel supply pipe, a water jacketed flaring nozzle detachably connected to said pipe, a collar surrounding said nozzle, an air blast box inclosing said collar, said collar being spaced from said nozzle and having apertures therein leading from the air blast box to the interior of the collar, an open-work fire brick hot box in alinement with said nozzle, and means in the nozzle supply pipe and in the collar surrounding said nozzle to produce whirling motion in 80 the fuel supply and in the collar air supply, respectively. 85

In testimony whereof I affix my signature.

JAMES JOHN CANTLEY BRAND.
